UNITED STATES PATENT OFFICE

158,481

PRACTICE KEYBOARD

Edgar T. Lugar, Berkeley, Calif.

Application July 13, 1948, Serial No. 147,517

Term of patent 3½ years

(Cl. D25—1)

To all whom it may concern:

Be it known that I, Edgar T. Lugar, a citizen of the United States of America and a resident of the city of Berkeley, county of Alameda, State of California, have invented a new, original, and ornamental Design for a Practice Keyboard, of which the following is a specification, reference being had to the accompanying drawing, forming a part thereof.

Figure 1 is a three-dimensional front view of the practice keyboard of my new design;

Figure 2 is a three-dimensional rear view thereof.

I claim:

The ornamental design for a practice keyboard, substantially as shown.

EDGAR T. LUGAR.
